Patented Sept. 14, 1965

202,296

CABINET FOR AUDIOVISUAL COMPONENTS

Noland E. Vogt, Menlo Park, and Frank T. Walsh, Palo Alto, Calif., assignors to Ampex Corporation, Redwood City, Calif., a corporation of California

Filed Sept. 12, 1963, Ser. No. 76,570

Term of patent 14 years

(Cl. D56—4)

FIGURE 1 is a front and side perspective view of a cabinet for audiovisual components, showing our new design, the back being substantially plain; and

FIGURE 2 is a front and opposite side perspective view of the cabinet for audiovisual components in an opened condition, the folded portions being conventionally plain.

The dominant features of our design reside in the portions shown in full lines in the drawing.

We claim:

The ornamental design for a cabinet for audiovisual components, substantially as shown and described.
